COMMUNICATION SYSTEM

Roy S. Pitkin, Jr., Rochester, Minn.

Application January 2, 1943, Serial No. 471,094

6 Claims. (Cl. 179—1)

My present invention relates to improvements in intra-communication systems of an amplified type, and it has been especially designed for military use and similar purposes. It is an aim of my invention to simplify the construction of apparatus of the character contemplated herein, and to improve the operation of said apparatus.

I have found that in military tanks, half tanks, armored trucks, planes, PT boats and like vehicles, extraneous noises are developed within the vehicle due to motors, vibrations and analogous noise producing equipment, such as exploding guns, and such extraneous noises are so great that communication between occupants of the vehicle is practically impossible. With this problem in mind, I have provided an intra-communication system which makes it possible for occupants of a vehicle which is subject to such extraneous noises, to converse between themselves without effort. I have also provided a communication system wherein such extraneous noises are substantially inaudible to the ears of the occupants, while the vocal sounds are readily audible.

For the purpose of disclosing this invention, I have shown my new and improved communication system installed in a military tank, but it is not my intention to limit this invention to use in military tanks as it will readily be apparent from the herein described apparatus that this invention may readily be adapted to be incorporated into other vehicles where the extraneous noises are so great that it is almost impossible to translate vocal sound waves.

When installed in a military combat tank for warfare and other uses, my new and improved apparatus is adapted to provide definite and continuous communication at all times between a central station and a plurality of substations, the commander of the tank occupying a position which will enable him to transmit and receive signals and messages from the central station, and the several members of his crew occupying positions in proximity to the respective substations, and vice versa, as all of the circuits are constantly open. With the exception of the headphones which are used by the commander, the employment by the crew of these instrumentalities and their accessories such as the lead cords and the like, is entirely eliminated in my intra-communication system so that there is no danger of such accessories becoming tangled or broken by the members of the crew who are constantly shifting positions or moving around at their stations in the constricted compartment within the tank body. In lieu of the portable headphones and

microphones which have heretofore been used by each member of the crew, my present system provides devices of this character as built-in equipment adjacent the respective stations of the crew which permits changing of the crews without requiring the members to remove their individual equipment as is now the practice. In other words, these separate instruments are standardized equipment which are permanently installed as a part of the tank.

I have ascertained, as a result of experiment and observation that the use of headphones and microphones by crews in the military tanks possesses a number of inherent disadvantages and objections which actually hinder the work of the crews, and they seriously reduce the efficiency of the individual members thereof. The standard army type of headphone becomes extremely hot and it is uncomfortable to wear due to the pressure which it exerts against the delicate cartilages of the human ear so that they may be worn only short periods of time by the crew members. Also, the fidelity of these instruments is unsatisfactory and is of relatively low order due to the fact that they lack damping means to eliminate the extraneous noises such as the roar of the operating vehicle and the sounds of the explosions of cannon and other weapons both inside and outside the tank so that the vocal sounds from the commander's microphone become mixed with these extraneous noises to such an extent that commander's vocal orders are indistinct and frequently are not discerned by crew members. In the structure disclosed I have overcome the above-mentioned disadvantages and objectionable features which are now present in the approved army equipment.

Within a certain type of military tank, the commander and 37 mm. gunner and loader occupy a mobile turret and the other crew members including the driver and the 75 mm. gunner and loader, inside the tank compartment must all use their hands, arms and feet in the performance of their respective duties and when engaged in combat it is extremely difficult if not impossible for them to manually grasp a microphone to converse with the commander. It therefore will be seen that the present use of portable microphones renders the tank less efficient when in action.

Another objection to the present army tank communication equipment resides in the fact that the crew members are subject to the constant roar of the tank operation and the gun-fire which is so intense at times that some of the men be-

come deafened and cannot hear the orders given by the commander. When my improved intra-communication system is used, the individual crew members may plug their ears to reduce the overall sound level and by increasing the volume of loud speakers at the crew stations, a greater ratio of voice to extraneous sounds will result so that the voice of the commander will become more intelligible to his crew.

In connection with structure contemplated herein I have devised a microphone structure which is of much smaller dimensions than those which have heretofore been employed in intra-communication systems of this character. The microphone is of the dynamic type and the diaphragm is exposed upon both sides to the extraneous sounds incident to the tank operation. This causes the extraneous sound waves to simultaneously strike upon both the front and rear sides of the diaphragm which will neutralize or balance the effect upon the diaphragm resulting in a cancelling or damping and non-vibration thereof. The diaphragm is suitably shielded so that the vocal sound waves of a crew member speaking into the microphone reach only one face of the diaphragm which will cause the latter to respond thereto and his voice heard by the commander.

From the foregoing it will be seen that, due to the shortcomings of the intra-communication system in vogue in the military tanks, the said system is inefficient and is incapable of satisfactory operation when the crew and tank is engaged in combat which is the time when the apparatus is most needed. In the novel and improved system which I have invented, the members of the crew do not wear headphones nor do they require portable microphones. The hands of the men are free at all times for the performance of their various duties and carrying out the commander's orders, and conversation between the commander and his crew is possible at any time since all that a member need do is merely speak into the microphone installed at his station and the voice is heard by the commander through his earphones which have been designed for comfort as well as to block out or damp the roar of the tank and its equipment. The commander's microphone is supported adjacent his mouth upon a short flexible holder that is attached to one or both of his headphones which permits him to speak to the crew at all times without changing his position and without physical effort. The volume of the loud speakers at the several crew stations is proportionately increased to permit the voice of the commander being distinctly heard above the tank roar which is greatly diminished to the crew's ears through the use of ear plugs, thus achieving a highly favorable voice to noise ratio. The crew members have very little difficulty in talking to the commander because I expose both faces of the diaphragm of the crew members' microphone to the extraneous sound waves to permit the extraneous sound waves to simultaneously strike the front and the rear faces of the microphones. This has a cancelling effect so that the diaphragms are practically inert in relation to the roar of the tank and the gun-fire, but since the diaphragm is especially designed to pick up the vocal sound waves upon only one of its sides, these vocal waves will cause a vibration of the diaphragm so that the voices are audible. Actual tests with my intra-communication system installed in tanks and under combat condi-

tions have disclosed the extraneous noises which are so harsh and violent that a person within the tank cannot hear his own voice when shouting at a high pitch, yet the microphone will pick up that person's voice waves when they are spoke from a distance of several inches from the microphone and will be distinctly heard through the commander's headphones to which these vocal sound waves are carried through an amplifier channel. The intra-communication system which I have invented is assembled as a unit so that it may be inserted into the standard Army approved shock-proof base where the usual radio receiver and transmitter are also installed in the body of the tank and it is adapted to be operated over the wires which are already installed for the equipment now being used.

Other advantages and aims of my present improvements will be apparent to persons skilled in the art after the construction and operation of my dual channel amplified intra-communication is understood from the within description. Among these additional aims or objects may be mentioned that my invention aims to provide an apparatus that possesses a high degree of novelty; which is efficient in the performance of its functions; which is made of sturdy and dependable parts so as to render it capable of withstanding severe usage; which is comparatively economical to manufacture; and which may be installed in military tanks now in use without altering the standard built-in structures and equipment.

I prefer to accomplish the above-mentioned and other objects and aims, and to practice my invention in substantially the manner herein-after described and as particularly pointed out in the appended claims. Reference is now made to the accompanying drawing which forms a part of this specification.

The drawing shows in diagrammatic form, of a more or less schematic character, a typical or preferred embodiment of my improved dual channel amplified intra-communication system, the various parts of the structure being illustrated by means of mechanical and electrical symbols.

In the intra-communication system shown in the drawing the central station occupied by the commander includes the receivers or headphones used by the commander and designated as 10 and his microphone 11, which is preferably of the magnetic type, and which is preferably mounted on a flexible support on the receiver or headphones structure, and it has relatively small dimensions as compared with the more or less standard types of devices being slightly over an inch in diameter and one-half inch in thickness. Said microphone is designed so that it may be disposed close to the commander's mouth to attain the best results from it, and its structure is such that it excludes extraneous sounds and operates at close range or almost touching the lips of the speaker. The microphone 11 is adapted to respond to frequencies of about 250 to 4000 cycles. As the range of hearing is approximately 40 to 18,000 cycles, it will be seen that the undesired sound waves outside the vocal range, those below 250 cycles and those between 4000 and 18,000 cycles, will be eliminated and the sound waves picked up will be only the predominant waves of 250 to 4000 cycles within the vocal range. The conductors 12 and 13 from microphone 11 are provided with an insulating shield 14 and they lead to respective terminals which bear the sym-

bolts "3" and "4" on the input device 15 and 16 which is a part of the central box 17. The conductor cord 18 from the headphones 10 is provided with a plug 19 which is removably inserted into the jack 20 in the control box 17 to establish connection with the volume control device 21 therein. Conductors 12a and 13a from the input device 15-16 in the microphone circuit, which are provided with an insulating shield 14a within the box 17, pass out of the latter and lead to dual channel amplifier devices which are constructed to adapt it to be removably installed as a unit in a convenient location within the compartment of the tank. The construction and dimensions of this amplifier device are such that the unit will fit the army standard receptacle within the tank without alteration and may be readily removed whenever desired.

In the diagram, the amplifier circuits for the commander and the crew have a common power supply schematically identified as 22. The elements in the amplifier circuit related to the commander's microphone 11 comprise the microphone input transformer 23, the input tube 24, and the output transformer 25, and the latter transformer 25 is electrically connected by conductor 26 with the terminal "1" of the receptacle 27 which coacts with corresponding prong "1" of the multiple prong plug 28. A volume control device 21' is inserted in the conductor 26. From the prong "1" a conductor 26a leads to one or more dynamic speakers 29, one of which is shown, which are placed at strategic locations or substations convenient to the different crew members, preferably at their respective stations. The input device 30 for the microphone 11 is connected by conductors 31 and 32 with input transformer 23, and conductors 33, 34 which have an insulation shield 35, lead to the respective terminals "2" and "3" of the receptacle 27.

Each crew member is provided at his substation, preferably adjacent his dynamic speaker, with his individual microphone, two of which, designated as 36a and 36b, are shown as connected in parallel to their input device 39 by conductors 37, 38 which are shielded by insulation 40. The amplifier circuit for the crew microphones is generally similar to the commander's amplifier circuit, although having much less power output, and consists of microphone input transformer 41, the input tube 42 and the output transformer 43. Shielded conductors 44, 45 connect the terminals "2" and "3" of the input device 39 with the input transformer 41. A conductor 46 leads from output transformer 43 to a jack 47 and a branch conductor 46a leads to a terminal "5" of the receptacle 27 which coacts with corresponding prong "5" of the multiple prong plug 28 from which prong "5" a non-shielded conductor 48 leads into the control box 17 and thence by conductor 48a to the volume control device 21. A volume control device 21" is inserted in the conductor 46.

The commander speaks into his central station microphone 11 and the sound waves are fed into the channel of the amplifier circuit, the upper circuit in the diagram, of the dual channel amplifier devices. The output of this amplifier circuit is then fed into the loud speakers at the crew stations or substations within the tank.

Since the microphone 11 is designed to operate at close range, and its structure is such that it will respond only to frequencies in the vocal range, 250 to 4000 cycles, it will consequently pick up sound waves which are predominately vocal to

the exclusion of extraneous or other sound waves outside the vocal range. The vocal sounds delivered by the speakers 29 are extremely loud in order to be heard above the noises of the tank and the gunfire. The microphone has no resonant pouch or cavity and therefore emits a flat response. The amplifier is also flat and the loud speakers reproduce a flat response.

The vocal sounds leaving the loud speakers at the several substations are quite loud and of considerable volume to the human ear drums of the crew. Their ears are plugged by muting plugs 50 to reduce the sound vibration upon the ear diaphragm and avoid injury thereto. The human ear will receive sounds as they become progressively louder up to a certain degree and thereafter the ear will be unable to translate the sound due to the natural structure of the ear to protect the nervous system to protect the person from intense head pains. The highest degree of sound which the average person can experience without pain is rated at about 125 db. (decibels) of sound, as compared with 109-113 db. of sound which I have ascertained is the normal degree of sound within the tank. I therefore increase the volume of sound issuing from the loud speaker to about 118 db. which is a degree where the oral sounds are so loud that they are well above the extraneous noises in the tank so as to be intelligible to the crew members, but since these vocal sounds are so extremely intense they must be muted by deafening the crew by means of plugs 50 inserted into their ears. This may cause a drop in sound volume reaching the ears to 90 db. (the tank noise) and the 118 db. voice to 95 db. Intelligibility at this degree may be found to be low but this is readily overcome by further increasing the volume of the loud speaker until the degree of sound reaching the ear drums is back to 118 db. Obviously this results in a highly favorable voice to noise ratio and results in a high degree of intelligibility.

The crew may converse with the commander by means of their dynamic microphones units 36a, 36b, etc., from whence the vocal waves are fed into the second channel of the amplifier and then to the commander's headphones 10. Each unit 36a is provided with a paper diaphragm and a moving voice coil and the diaphragm is exposed on both sides to allow the tank noises and gun fire sound energy to hit the front and back faces and cancel out the extraneous noises because there is no apparent motion in the voice coil. The voice of a crew member will hit the front of this diaphragm and thus a very favorable ratio of vocal sound waves to extraneous sound waves is attained.

Although but one specific embodiment of this invention is herein described, it is to be understood that some of the details set forth may be altered or omitted without departing from the spirit of the invention as defined by the following claims.

I claim:

1. An intra-communication system for vehicles of the enclosed type wherein noises from extraneous sources are inherent embodying a central station microphone; a substation microphone; dual channel amplifier circuits for said microphones; a common power supply for said amplifier circuits; each said circuit consisting of an input transformer, an input tube, and an output transformer; a loud-speaker in one of said amplifier circuits; headphones in the other of said amplifier circuits; one of said microphones

being in circuit relation with said loud-speaker and the other of said microphones being in circuit relation with said headphones, control means in said loud-speaker amplifier circuit effective to raise the volume of sound delivered by said loud-speaker to a level above that of the extraneous noises and above the level of sound volume that the human ear can safely receive, and sound modifying means interposed between the loud-speaker and the ear of the operator in proximity thereto and positioned to be traversed by sound waves from said loud-speaker and from said extraneous sources to simultaneously reduce the volume of sounds delivered to the ear of said operator to a level within the range of sound volume that can be safely received by the human ear, to thereby increase the differential of sound volume between the noises from said extraneous sources and the signal sounds as received by said operator.

2. In an intra-communication telephone system including a central station and a substation, each comprising a microphone and a receiver, and both stations being positioned in an environment characterized by the presence of high decibel noises from extraneous sources, means to increase the volume of signal sound from the receivers to a decibel level above that of the noises from said extraneous sources and above that which the human ear can safely receive, and muting means interposed between the said receivers and the ears of operators effective to reduce simultaneously and in corresponding amount the decibel level of both the extraneous sounds and signal sounds to within a decibel range which the human ear may safely receive to thereby increase the differential between the decibel level of the signals and of the sound from said extraneous sources as received by the operator.

3. In an intra-communication telephone system including a central station and a substation, each comprising a microphone and a receiver, and both stations being positioned in an environment characterized by the presence of high decibel noises from extraneous sources, means for neutralizing the effect of sound from said extraneous sources upon said microphones, means to increase the volume of signal sound from the receivers to a decibel level above that of the noises from said extraneous sources and above that which the human ear can safely receive, and muting means interposed between the said receivers and the ears of operators effective to reduce simultaneously and in corresponding amount the decibel level of both the extraneous sounds and signal sounds to within a decibel range which the human ear may safely receive to thereby increase the differential between the decibel level of the signals and of the sounds from said extraneous sources as received by the operator.

4. In an intra-communication telephone system including a central station and a substation, each comprising a microphone and a receiver, and

both stations being positioned in an environment characterized by the presence of noises from extraneous sources of a volume close to but less than the upper decibel level which the human ear may safely receive, means to neutralize the effect of the sound waves from said extraneous sources upon said microphones, means to increase the volume of signal sound from said receivers to a decibel level above that of the extraneous noises and above that which the human ear can safely receive, and muting means interposed between the said receivers and the ears of the operators effective to reduce simultaneously and in corresponding amount the decibel level of both the extraneous sounds and signal sounds to within a decibel range which the human ear may safely receive to thereby increase the differential between the decibel level of the signals and the sounds from said extraneous sources as received by the operators.

5. In an intra-communication telephone system including a central station and a substation each comprising a microphone, the substation including a loud-speaker receiver, and both stations being positioned in an environment characterized by the presence of high decibel noises from extraneous sources, means to neutralize the effect of the sound waves from said extraneous sources upon said microphones, means to increase the volume of signal sound from said loud-speaker to a decibel level above that of the extraneous noises and above that which the human ear can safely receive, and muting means adapted to be disposed in the ears of operators at said substation and effective to reduce simultaneously and in corresponding amount the decibel level of both the extraneous sounds and the signal sounds from the loud-speaker to within a decibel range which the human ear may safely receive to thereby increase the differential between the decibel level of the signals and of the sounds from said extraneous sources as received by the operators.

6. In an intra-communication telephone system including a central station and a substation each comprising a microphone and a receiver, the receiver of the substation being in the form of a loud-speaker, and both stations being positioned in an environment characterized by the presence of high decibel noises from extraneous sources, means for neutralizing the effect of sound from said extraneous sources on said microphones, means to increase the volume of signal sound from the loud-speaker to a decibel level appreciably above that of the noises from said extraneous sources, and muting means adapted to be disposed in the ears of an operator at the substation and effective to simultaneously reduce and in corresponding amount the decibel level of both the extraneous sounds and signal sounds to thereby increase the differential between the decibel level of the signals and of the sounds from said extraneous sources as delivered to said operator.

ROY S. PITKIN, JR.
